UNITED STATES PATENT OFFICE.

WILLMOT G. HOFFMAN, OF SAN FRANCISCO, CALIFORNIA.

UMBRELLA.

No. 805,957.

Specification of Letters Patent.

Patented Nov. 28, 1905.

Application filed May 14, 1904. Serial No. 208,024.

To all whom it may concern:

Be it known that I, WILLMOT G. HOFFMAN, a citizen of the United States, residing at San Francisco, in the county of San Francisco and State of California, have invented new and useful Improvements in Umbrellas, of which the following is a specification.

This invention relates to umbrellas of that type which are adapted to be folded into small compass and carried in a coat-pocket or valise and is so constructed that it will be light and strong, quickly opened and closed, and free from the annoyance occasioned by the entanglement of the ribs, a fault common to this and other types of umbrellas.

In the accompanying drawings, Figure 1 represents an elevation of my umbrella-frame opened, the ribs being bowed as they would appear when covered. Fig. 2 is an enlarged view of the umbrella-frame closed. Fig. 3 is an enlarged vertical sectional view through the telescope-stick. Figs. 4 and 5 are detail views of the rib-joints in different positions. Fig. 6 is a view of the joint from the inside. Figs. 7, 8, and 9 are perspective views of the joints.

Similar letters refer to the same parts on all the figures.

A indicates a telescopic umbrella-stick, to the upper end of which is attached a notch-ring F, in which supporting-ribs, hereinafter specifically described, are pivoted, they being expanded by the stretchers C, pivoted to said supporting-ribs and to a runner D. The handle is indicated by E. The stick A is in three tubular parts—the lower section A', to which is attached a handle E, the upper section A², bearing a notch-ring F on its top end, and the intermediate section A³, telescopically connected to the two end sections. The lower ends of the intermediate and upper sections A² A³ are enlarged externally to form shoulders a² a³, respectively, which when the stick is extended abut against similar shoulders a' a' within the upper ends of the respective lower and intermediate sections A' A². A spring-catch a⁴, riveted to the inside of the intermediate section A², projects through a slot near its lower end and engages the upper end of the lower section when the parts are extended. A similar spring-catch a⁵ holds the intermediate and upper parts in fixed position when drawn out.

The runner D has its upper half fitted to slide smoothly on the upper section A³ of the stick and its lower half enlarged, as at D', to

permit the intermediate section entering thereinto when the umbrella is folded. A notch-ring G is attached to the upper end of the runner D, in which notch-ring the stretchers C are pivoted at one end.

The cover-supporting ribs are each formed of two substantially equal parts H and I, hinged together at B'. The inner end of part H of each rib is pivotally connected to 65 the notch-ring F, while the outer end of each part I is perforated to receive the thread by which the cover is secured to the ends of the ribs. The stretchers C, pivoted as hereinbefore mentioned to the runner D, have attached to their outer ends joint-tips c, right angular in shape and connected by pin-joints to the parts I just above the joints B' of the ribs. (See Figs. 7 and 8.) The joint B' between the rib parts H and I is constructed as 70 clearly shown in Figs. 6, 7, 8, and 9, where it will be seen that the jointed ends of the parts H and I are secured in sockets H' and I', respectively. The socket H', longer than I', has a hook-shaped finger h at one side 75 which extends under the rib I to limit its movement and give it support when the umbrella is opened. The sockets H' I' have lugs projecting downwardly from their adjacent sides through which the pivot-pin 80 passes. The inner end of the rib part I passes beyond its socket I' sufficiently far to hinge the stretcher thereto. Placing the pivotal points B' of the rib parts H and I under the rib enables me to present a smooth 85 comparatively unbroken upper surface for the cover.

The umbrella being folded as represented in Fig. 2, it will be seen that the joints B' of the cover-supporting ribs and between the 90 ribs and stretchers are at the lower or handle end of the stick and held closely thereto by a depression e in the under side of the handle. To open the umbrella, it is held in one hand, the other hand drawing out the handle E for a short distance to release the ribs and stretchers, which spread out, as indicated in dotted lines in Fig. 2, they having been drawn inward for engagement with the handle and held by the handle under spring tension by 95 reason of the stretchers C bearing against and being intermediately held out from the stick by the enlarged portion D' of the runner D. The hand which heretofore held the umbrella now takes hold of the runner and pulls the 100 handle, drawing the stick out to its full length. The catches a⁴ a⁵ then spring into place and 105

lock the stick. The runner is then drawn down until it is caught by the snap L. The ribs will then be fully spread.

The cover is fastened at the ends of the ribs and at other suitable points thereon. I also propose to carry the ribs in pockets formed by the cover-seams.

Having thus described the invention, what is claimed is—

- 10 1. In an umbrella, the combination of a stick comprising three telescopic sections, means for holding said sections extended, a runner slideable on the upper stick-section and having an enlarged portion to receive the intermediate stick-section when the stick is telescoped, folding supporting-ribs pivoted to the upper stick-section, each rib comprising two parts having sockets at their meeting ends pivotally connected with each other,
- 15 2. the socket on one part having a hook to engage the other part and the latter having a pivot-lug, stretchers pivoted to the runner and to the pivot-lugs of the ribs and adapted to engage intermediately of their ends the enlarged portion of the runner and to be held away from the stick thereby when said

stretchers and ribs are closed, and a handle on the lower stick-section provided with a depression to receive the hinged ends of the folded ribs and stretchers when the latter are drawn toward the stick, whereby the joined ends of the ribs and stretchers will be held under spring tension, substantially as described.

30 2. In a folding umbrella, the combination of ribs, each formed in two parts, a socket on each part having a lug for a hinge-pin, and a finger or hook projecting from the socket on one part adapted to support the second part when extended.

35 3. In a folding umbrella, the combination of ribs each formed in two parts, a socket on each part having a lug for a hinge-pin, a finger or hook projecting from the socket, on one part adapted to support the second part when extended, and a stretcher pivoted to the end of said second part.

40 In testimony whereof I affix my signature in presence of witnesses.

WILLMOT G. HOFFMAN.
